United States Patent Office

Des. 213,428
Patented Mar. 4, 1969

213,428

PACKAGING TUB

Danny J. Batdorf, Toledo, Ohio, assignor to Owens-Illinois, Inc., Toledo, Ohio, a corporation of Ohio

Filed Feb. 23, 1968, Ser. No. 10,685

Term of patent 14 years

U.S. Cl. D9—220
Int. Cl. D9—02

FIG. 1

FIG. 2

FIG. 3

The side not shown is a mirror image of the side shown.

I claim:

The ornamental design for a packaging tub, substantially as shown and described.
